UNITED STATES PATENT OFFICE.

WALTER B. CLARK, OF LINCOLN PARK, MICHIGAN, ASSIGNOR OF ONE-HALF TO I. D. LAWRENCE, OF DETROIT, MICHIGAN.

WINDOW SHIELD.

Application filed June 30, 1927. Serial No. 202,588.

This invention relates to improvements in window shields and more particularly to a shield for the window openings for the tellers in banks, and other financial institutions.

One object of the invention is to provide a window shield with operating mechanism which may be rendered operative simply by the closing of an electrical circuit.

Another object is to provide a window shield which, after having been moved to window closing position, may be utilized to give an audible signal.

A further object is to provide a comparatively simple operating mechanism which requires little, if any, attention to maintain it in sound operative condition.

With these and other objects in view the invention consists in certain novel details of construction and combinations and arrangements of parts, all as will hereinafter be more fully described and the novel features thereof particularly pointed out in the appended claims.

In the accompanying drawings,

Figure 1 is a top plan view of the mechanism constituting the present invention.

Fig. 2 is a transverse vertical sectional view taken centrally of the structure shown in Fig. 1; and

Fig. 3 is a front elevational view.

In accordance with the present invention a housing 10 is adapted to be suitably mounted above the window opening to be protected and in said housing there is a vertically disposed slot 11 extending substantially throughout the length of said housing. Positioned in said slot 11 is the shield 12.

When in its normal position above the window opening it is adapted to be supported by bolts 13 slidably housed in the housing 10, said bolts preferably projecting into slot 11 between the lower edge of shield 12. As shown, the bolts 13 are located in the holes drilled in housing 10, said holes being closed at their exposed ends by plugs 14. Interposed between each plug and bolt is a spring 15 for yieldingly urging the bolt toward slot 11 into engagement with shield 12.

For retracting the bolts 13 in cases of emergency a shaft 16 is journaled in suitable bearings on housing 10, said shaft carrying a plurality of pins 17 capable of engaging projections 18 (also preferably in the form

of pins), shaft 16 being connected to and driven by a small motor 19 mounted on the housing, operation of said motor being controlled by a switch (not shown) which, as will be understood, can be suitably located in the teller's cage or at a point where it can be readily reached by a person standing behind the window to be protected.

When the switch, which may be an ordinary push button, is closed motor 19 will rotate shaft 16, and when pins 17 strike projections 18 on bolts 13 the latter will be retracted from the path of shield 12 whereupon the latter will be free to fall by gravity to close the window opening. So long as the motor is kept in operation the bolts 13 will be caused to travel back and forth in the housing so that they will be caused to constantly hit against the lower shield and produce a hammering effect. This result, which may serve as an alarm, will be produced by the fact that each time the bolt 13 is retracted and spring 15 depressed, said spring will throw the bolt back against the lowered shield immediately upon disengagement of pin 17 and projection 18 by the continuous rotation of shaft 16. The tone produced by this hammering effect will depend upon the nature of the materials used, although shield 12 should, of course, be bullet-proof. Likewise, the violence with which bolts 13 are thrown against the lowered shield will depend upon the strength of springs 15. To prevent turning of bolts 13 so that pins 18 may not accidentally move out of the path of pin 17, said bolts may be provided with suitable projections 20 adapted to be guided in slots 21 in housing 10.

For elevating the shield from its window closing position to its normal position above said window a rack 22 is provided on said shield at each end thereof, each rack meshing with a pinion 23 on a shaft 24 extending lengthwise of the housing and on said shaft there is also a gear 25 adapted to engage with a gear 26 on a shaft 27 also journaled on the housing. Shaft 27 carries a larger gear 28 and when it is desired to operate the train of gears just described the slidable gear 29 is adapted to be clutched into mesh with gear 28 by means of a suitable operating lever 30. It will be understood that gear 29 is normally disengaged from gear 28 in

order to permit shield 12 to fall by gravity when the supporting bolts 13 are moved out of opening 11.

What I claim is:

- 5 1. In a device of the character described, a vertically movable shield adapted to be normally positioned above a window opening, releasable means for retaining said shield in normal position, means for releasing said retaining means whereby said shield will move by gravity to close the window opening, a driven shaft and means operable by said shaft for elevating said shield from closed to normal position.
- 10 2. In a device of the character described, a shield, means directly supporting said shield above a window opening, means for withdrawing said supporting means, whereby said shield will fall by gravity to window closing position, a driven shaft and means operable by said shaft for elevating said shield to its position above the window.
- 15 3. In a device of the character described, a shield, supports yieldingly positioned beneath the shield for normally supporting it above a window opening, and means for repeatedly retracting said supports away from the shield whereby said shield will first drop to window closing position, and said supports will subsequently be reciprocated back and forth against the shield in such closed position.
- 20 4. In a device of the character described, a housing having a vertically disposed opening therein, a shield slidable in said opening, bolts in said housing and normally projecting into said opening and constituting a support for said shield to normally position it above a window opening, and power driven means for retracting said bolts from said opening whereby the shield will be free to drop by gravity to window closing position.
- 25 5. In a device of the character described, a housing having a vertically disposed opening therein, a shield slidable in said opening, bolts in said housing and normally projecting into said opening and constituting a support for said shield to normally position it above a window opening, power driven means for retracting said bolts from said opening whereby the shield will be free to drop by gravity to window closing position, and means adapted to be connected to said power driven means for elevating said shield from closed position to its normal position above the window opening.
- 30 6. In a device of the character described, a housing having a vertically disposed opening therein, a shield slidable in said opening, bolts slidable in said housing and normally positioned in said opening to support the shield above the window opening, power driven means for retracting said bolts from said opening whereby the shield will be free to drop by gravity to window closing position, and means for urging said bolts toward said opening and shield, said power driven means for retracting the bolts being adapted to be continuously operated when the shield is in closed position whereby said bolts will be constantly reciprocated back and forth against said shield when the latter is in its closed position.
- 35 7. In a device of the character described, a housing, a shield vertically movable in said housing, supporting elements in said housing for normally holding said shield at a point above a window opening, and means for reciprocating said supporting means back and forth against said shield when the latter has moved downwardly in the housing to window closing position.
- 40 8. In a device of the character described, a housing, a shield vertically movable in said housing, bolts slidably mounted in said housing, means for yieldingly urging said bolts in one direction into engagement with said shield to support the latter in a position above the window, a projection on each of said bolts, and means for periodically engaging said projection and moving said bolt away from said shield whereby when said bolt is first moved from engagement with said shield the latter will be free to drop into window closing position and thereafter said bolts will be reciprocated back and forth against said shield.
- 45 9. In a device of the character described, a housing, a shield vertically movable in said housing, bolts slidable in said housing, means for yieldingly urging said bolts into engagement with said shield to support the latter in a position above a window opening, a projection on each of said bolts, a shaft journaled on said housing, pins on said shaft adapted to periodically engage the projections on said bolts, and means for rotating said shaft.
- 50 10. In a device of the character described, a housing, a shield vertically movable in said housing, bolts slidable in said housing, means for yieldingly urging said bolts into engagement with said shield to support the latter in a position above a window opening, a projection on each of said bolts, a shaft journaled on said housing, pins on said shaft adapted to periodically engage the projections on said bolts, power driven means for rotating said shaft, and connections between said power driven shaft and said shield for raising the same from its window closing position to its normal position above the window.

WALTER B. CLARK.

CERTIFICATE OF CORRECTION.

Patent No. 1,666,773.

Granted April 17, 1928, to

WALTER B. CLARK.

It is hereby certified that the name of the assignee in the above numbered patent was erroneously written and printed as I. D. Lawrence, whereas said name should have been written and printed as J. D. Lawrence, as shown by the records of assignments in this office; and that the said Letters Patent should be read with this correction therein that the same may conform to the record of the case in the Patent Office.

Signed and sealed this 29th day of May, A. D. 1928.

(Seal)

M. J. Moore,
Acting Commissioner of Patents.
